(57) **CLAIM**

(21) Appl. No.: **29/248,631**

The ornamental design for a hinge for flush mount enclosure, as shown and described.

(22) Filed: **Aug. 24, 2006**

DESCRIPTION

(63) Continuation-in-part of application No. 11/138,071, filed on May 26, 2005.

FIG. 1 is a perspective view of a hinge for flush mount enclosure, incorporating the new design; the hinge for flush mount enclosure is shown in condition of use mounted onto the front of a broken line electrical enclosure with two additional broken line hinges. All broken lines shown are for illustrative purposes only and form no part of the claimed design.

(51) **LOC (8) Cl.** **08-06**

FIG. 2 is a front view of a hinge for flush mount enclosure, incorporating the new design; the hinge for flush mount enclosure is shown in condition of use mounted onto the front of a broken line electrical enclosure with two additional broken line hinges. All broken lines shown are for illustrative purposes only and form no part of the claimed design.

(52) **U.S. Cl.** **D8/323**

FIG. 3 is a perspective view of the hinge for flush mount enclosure of FIG. 1;
